ATTORNEY

UNITED STATES PATENT OFFICE.

ETHELBERT R. FREDERICK, OF EAST ORANGE, NEW JERSEY, ASSIGNOR TO HAVONE CORPORATION, OF NEW YORK, N. Y., A CORPORATION OF NEW YORK.

CIGARETTE-CASE.

1,271,884.

Specification of Letters Patent.

Patented July 9, 1918.

Application filed June 1, 1915. Serial No. 31,385.

To all whom it may concern:

Be it known that I, ETHELBERT R. FREDERICK, a citizen of the United States, and resident of East Orange, in the county of 5 Essex and State of New Jersey, have invented certain new and useful Improvements in Cigarette-Cases, of which the following is a specification.

My invention relates to cases for holding 10 cigarettes or other articles, and particularly to cases comprising a central holder adapted to receive such articles, and its object is to provide a device of simple construction, which can be manufactured at low cost, and 15 whose parts can be easily assembled.

Two embodiments of my invention will now be described with reference to the accompanying drawings, and the novel features will be pointed out in the appended 20 claims.

In the said drawings, Figure 1 is a vertical section of the cigarette case in the open position, taken on line 1—1 of Fig. 2; Fig. 2 is a vertical section on line 2—2 of Fig. 1; 25 Fig. 3 is a bottom view of the holder proper; Fig. 4 is a partial cross section similar to Fig. 1, but on an enlarged scale; Fig. 5 shows the same parts as Fig. 4, but with the case in the closed position; Fig. 6 is a view 30 similar to Fig. 2, but showing another form of my invention; Fig. 7 is a bottom view of the holder shown in Fig. 6; and Figs. 8 and 9 are partial sections of this modification, the views corresponding to those shown in 35 Figs. 4 and 5.

In the preferred form of my invention, shown in Figs. 1 to 5 inclusive, the case comprises two lids or covers A, B, formed at one edge with hinge sleeves or eyes A', B' respectively, through which extends a pintle 40 C, the hinge eyes A', B' alternating with each other. At its central portion the pintle C carries a spiral spring D which tends to swing the lids A, B apart in the customary manner. The pintle C is also adapted to pass through eyes E' formed at one end of arms or brackets E, the other ends of which are secured to the bottom of the holder proper F. This holder is preferably made 45 of corrugated sheet metal, so as to form pockets or seats for the cigarettes or similar articles to be carried in the case. Plates or wings G pivoted to the holder at G' and pressed toward it by suitable springs G''

(Fig. 2) are adapted to hold the cigarettes 55 in said pockets. A catch or clasp a, a' of any suitable character is provided to hold the case in the closed position.

In order to keep the holder firmly in a position midway between the two lids, when 60 the case is opened, hooks F', F'' are formed on the bottom of the holder on opposite sides and near opposite ends thereof; that is, one hook, F', will be on one side of the holder at or near one end, and the other hook, F'', 65 will be on the other side, at or near the other end. The free ends of these hooks extend downwardly and inwardly and are adapted to engage hook-shaped extensions A'', B'' respectively of the lids A, B; the extension 70 A'' is formed on the lid A at or near one end of the hinge so as to come into engagement with the hook F' when the case is swung open, while the other extension, B'', is formed on the lid B at or near the other 75 end of the hinge, so as to come into engagement with the hook F''. With the case in the closed position, the hook-like extensions or hooks A'', B'' will be out of engagement 80 with the hooks F', F'', as shown in Fig. 5; 85 when the case is opened and the lids are swung apart by the action of the spring D, the hooks A'', B'' will come into engagement with the hooks F', F'', thus bringing the holder F into a position midway between 90 the two lids and holding it firmly in this position. This will also limit the opening movement of the case, as the lids can not swing apart farther than the position shown in Figs. 1 and 4. It will be seen that 95 as long as the case remains in the fully opened position, the holder can not be swung either to one side or the other, the hooks A', B'' preventing such movement.

In the modification shown in Figs. 6 to 95 9, the lids and holder proper are of the same general construction as in Figs. 1 to 5. In Fig. 6 the plate G hinged to the holder has been omitted merely to simplify the drawing. In this second form, however, the 100 holder proper is not connected with the hinge of the case, that is to say, the brackets E with their eyes E' are omitted. In order to secure the holder within the case, the bottom of the holder F* has or is formed 105 with, two pairs of hooks F², F³ adapted to be engaged by a corresponding number of hook-shaped extensions A², B³ formed on

the lids A², B² respectively, at their portions adjacent to the hinge. The hooks F², F³ all face inward with their open portions and are disposed in such a manner that the 5 hooks F² will be engaged by the hooks A³ on the lid A², and the hooks F³ by the hooks B³ on the lid B².

The operation of the case is the same as described in connection with the preferred 10 form of my invention. The hooks of course will be of such a shape that even in the closed position of the case they will be in engagement (see Fig. 9). In order to prevent lateral movement of the holder after it 15 has been mounted in the case, I prefer to make the holder bottom with small extensions F⁴ at the two ends, which are originally in the position shown in dotted lines in Fig. 7. The lids being in the position 20 Fig. 8, the holder proper can then be slipped on endwise (parallel to the hinge), whereupon the extensions F⁴ are bent downward, as shown in Fig. 6, thus preventing the holder from being moved laterally of the 25 case.

Various modifications may be made without departing from the nature of my invention as set forth in the appended claims. Thus the number of hooks used may be 30 varied, and furthermore it is not essential that the hooks be integral with the parts from which they project. By suitably choosing the dimensions, the case may be adapted to hold articles other than cigarettes.

35 I claim:

1. A case of the character described, comprising a pair of hinged lids provided, near the ends of their hinged portions, with hooks facing in opposite directions, and a 40 holder located between the lids and connected with the hinge thereof, said holder being provided, near one end, with a hook extending in one direction to engage the hook on one of the lids, and also provided, 45 near the other end, with a hook extending in the opposite direction to engage the hook.

on the other lid, said holder hooks being secured to the holder rigidly.

2. A case of the character described, comprising a pair of hinged lids provided at 50 their hinged portions with hooks facing in opposite directions, the hooks which are on different lids, lying in different transverse planes, with respect to the hinge axis, and a holder located between said lids and connected therewith, said holder being provided with a hook facing in one direction and engaging a hook on one of the lids, and with another hook, lying in a different transverse plane and facing in the opposite direction, 55 to engage a hook on the other lid, said holder hooks being in fixed relation to the holder.

3. A case of the character described, comprising a pair of hinged lids provided, near 60 the ends of their hinged portions, with lugs facing in opposite directions, and a holder located between the lids and connected with the hinge thereof, said holder being provided, near one end, with a lug extending in one direction to engage the lug on one of the 65 lids, and also provided, near the other end, with a lug extending in the opposite direction to engage the lug on the other lid, said holder lugs being secured to the holder rigidly.

4. A case of the character described, comprising a pair of hinged lids provided at 70 their hinged portions with lugs facing in opposite directions, the lugs which are on different lids, lying in different transverse planes, with respect to the hinge axis, and a holder located between said lids and connected therewith, said holder being provided with a lug facing in one direction and engaging a lug on one of the lids, and with 75 another lug, lying in a different transverse plane and facing in the opposite direction, to engage a lug on the other lid, said holder lugs being in fixed relation to the holder.

75 In testimony whereof, I have hereunto set 80 my hand.

ETHELBERT R. FREDERICK.
